ELECTRONIC CODE-TYPEWRITER SYSTEM

Nathaniel G. A. Dorfman, New York, N. Y.

Application April 16, 1952, Serial No. 282,665

2 Claims. (Cl. 178—17)

1

The present invention is concerned with improvements in the art of code communication and particularly with respect to devices for facilitating and improving the quality and ease of such communication.

The advantages of code communication over direct voice communication, particularly with respect to reliability of transmission of intelligence, are well known. However, one of the factors which has prevented the utilization of code communication to its fullest extent has been the erratic production of code characters necessarily implicit in manual sending due to such factors as operator fatigue or lack of skill, and limitations on the speed of transmission, which is generally slower than speeds of reception of which ordinary operators are capable. In addition, each operator has personal idiosyncrasies of sending individual to himself which in many instances permit recognition of the operator by these characteristics, termed "signature."

In order to avoid some of the disadvantages or drawbacks implicit in such manual communication, recourse has been had to automatic systems. While the long established system of code communication has been the International Morse code, it has been found that the International Morse code, by virtue of the haphazard manner in which it was originated, is not adapted to efficient automatic communication, and, as a result, substantially all automatic code communication systems have devised special code arrangements, of which a common example is the teletypewriter code, which are required for efficient utilization of automatic devices for code communication. However, such automatic systems require special receiving machines in addition to special sending machines, and reception cannot be interpreted by an operator directly and audibly.

The most desirable solution to these problems would be an apparatus which would produce uniform, high quality, code characters utilizing a minimum of manipulative skill at the transmitting end and in a code which could be received directly and audibly by operators without requiring any special receiver apparatus other than the conventional code receiver now in customary use. It would further be desirable to provide such a transmitting apparatus with a greater speed of transmission than can be readily obtained manually, except by the most highly skilled and experienced operators, while still within the normal range of reception speeds of the average code receiver operator. As is well known, there is considerably less difficulty in receiving at higher speeds than transmitting at such higher speeds.

2

The present invention accomplishes these purposes and supplies a machine having a typewriter keyboard operated exactly the same as a typewriter, and which produces electrical code signals suitable for transmission to a receiver in any known manner, such as by direct wire or carrier modulation, either by wire or radio link.

According to the present invention any desired code may be utilized. In the following detailed description of the present invention, the International Morse code is used by way of example, since it is probably the most complicated of the code systems which have been suggested for use. The principles of the present invention, however, are equally applicable to any type of code arrangement, and practically any other system suggested will offer less complication and be a simplification of the apparatus herein disclosed.

The present invention particularly pertains to improved methods and apparatus for radio and wire communication and more particularly to methods and apparatus for forming electrical code signals by electronic means operating in response to a keyboard which may be similar to that of a standard printing typewriter. The electrical signals thus produced may be used in any desired manner and, for example, may be substituted for the signals created by standard hand operated telegraph key to be subsequently transmitted to a receiving station in any desired manner.

A particular advantage of the present system resides in an extremely simple adjustment for the speed of transmission permitting setting the basic timing rate to any desired value between low and high extremes of the order of 5 to 125 words per minute.

When applied to Morse code, whose code characters are made up of dots, dashes and spaces, with dots and spaces of equal duration and dashes of three times that duration, the present invention offers extreme simplicity in using what I term the Series Sequence System, which does not require separate generation of dot signals, space signals and dash signals, plus provision for intermixing these signals. According to the present invention, a single sequence of uniform duration pulses is produced for each character, with an overall sequence length coordinated to the length of the character being sent, and dots, spaces and dashes are formed in proper number and sequence by controlling in simple manner the passage or blocking of the pulses of that sequence. The number of pulses required in the sequence, and the blocking or passing of appropriate pulses to form the desired character, are

performed automatically merely upon depressing the keyboard key corresponding to such desired character.

These and other features are made possible by the use of special principles and apparatus forming the present invention, other objects and advantages of which will become more fully apparent from consideration of the following detailed description of an illustrative embodiment thereof, taken in conjunction with the appended drawings, in which:

Figure 1 is a schematic block diagram of the entire system embodying the present invention;

Figure 2 is a chart of the Morse code arranged with all characters terminating to show the principles of the invention;

Figure 3 is a fragmentary schematic circuit diagram showing portions of the unit interval generator chain, the keyer section, the sequence selector section, and the eraser and monitor sections of the present invention;

Figure 4 is a fragmentary circuit diagram of portions of the keyboard and phantom switch network of the present invention.

Basic principles

Before describing in detail the apparatus illustrating the present invention, a brief discussion will be given of its basic principles. The International Morse code as is well known, consists of some 43 different sequences of dots and/or dashes in different combinations, each combination representing a character, such as a digit or a letter of the alphabet, or punctuation mark, or a special code symbol, such as BT, AR, AS or SK, each such character having its individual code representation in dots and dashes. The interval forming the dash is by standard convention three times the time interval forming a dot. Also, the spacing between two successive dots or dashes of the same character is standardized as equal to the time interval of one dot.

A basic principle of the present invention is the use of the dot (or space) duration as a unit time interval with respect to which all time relations are coordinated. Since the dash interval is also coordinated to and based upon this unit interval, the total time duration of any particular character is solely dependent upon the unit interval. As one important feature of the invention, described in detail below, the unit interval is made adjustable very simply, thus rendering the speed of transmission adjustable at will.

In the Morse code the total duration of code character, as measured in unit intervals, varies from one unit interval for the letter E, whose code symbol is a single dot, to 19 unit intervals for the digit zero (whose code character is five dashes with four spaces) and for the comma (two dashes, two dots, two dashes with six spaces). Other characters have varying durations between 1 and 19 unit intervals. Because of this variation in the duration of code characters, it is not practicable to devote a constant time interval to each character, since that would waste a considerable portion of the interval for the shorter characters. It is then necessary that the characters be allotted varying time intervals corresponding to the number of unit intervals involved in each.

This is readily accomplished in the present system, by the selection of the end of each character as a reference datum, and controlling the instant of commencement of the characters in accordance with the number of intervals it has.

This is illustrated in Figure 2, which shows the Morse code in terms of the unit intervals, with all characters terminating with interval 19. It will be seen that the nature of this code makes all characters have an odd number of unit intervals, and all characters start at the beginning of the odd-numbered unit intervals, with all odd unit intervals thereafter being marks (that is, dot or portions of dashes). Also, all spaces fall into the even-numbered unit intervals, but not all such even unit intervals are spaces, some being marks, such as interval 18 in the letter A.

While the present invention is capable of use with any general code system, the above characteristics permit some simplifications when using Morse code. Thus, after the initiation of a code character is accomplished after proper interval number, it is necessary to control only the even-numbered intervals therebeyond, as to being a space or a mark, in order to form the proper code character.

The present system produces an output signal represented by the opening and closing of a pair of contacts of a keying relay, corresponding exactly to the opening and closing of a manual telegraph key, to produce marks during closed intervals and spaces during open intervals. Thereby, a primary use of the present apparatus is in direct substitution for a manual telegraph key or its equivalent. The keying relay is operated in response to an electric current passing through its winding and having a pulsed wave form corresponding to the output signal, with short (unit interval) pulses for dot marks and long (3-unit) pulses for dash marks.

To provide the varying combinations of dot pulses, dash pulses and spaces, the present system has a generator section which for each character to be transmitted produces a number of uniform-duration electrical pulses equal to the number of unit intervals in that character. These pulses are supplied to a keyer section which is controlled so as to pass to the output keyer relay only those pulses required to make up the marks for the character, a dot mark being formed by a single pulse and a dash mark being formed by three successive pulses. The keyer section is controlled by a sequence selector section which in turn is operated by a keyboard through a special phantom-switch network.

The general system

As shown in Fig. 1, the system comprises a chain of cascaded unit interval generators UIG1, UIG2, etc., equal in number to the largest number of unit intervals in the code system employed, being 19 in Morse code. These 19 generators UIG1 to UIG19 are connected in a cascaded chain arrangement and are normally in a quiescent state. When any one generator is triggered it produces a rectangular pulse and triggers the next generator at the end of that rectangular pulse; that generator in turn similarly produces a rectangular pulse and triggers the following generator, and this action is repeated until the end of the chain.

The generator chain is controlled by a keyboard KB, preferably arranged in a fashion similar to a typewriter keyboard, and having 43 Morse code characters plus a "clear" or checking key CL. Upon depressing one of these keys, a trigger pulse is supplied to the generator chain, at a point such that there are as many unit interval generators following that point as there are unit intervals in the code character repre-

sented by the depressed key. The generator chain then produces a sequence of successive uniform-duration rectangular pulses equal in number to the unit intervals in the code character.

Each of the unit interval generators UIG_1 to UIG_{19} is coupled to a respective keyer K_1 to K_{19} . Each of the even keyers is a gated tube, controlled by a respective sequence selector SS_2 to SS_{18} (in Morse code, the odd keyers K_1 , K_3 , etc. do not have to be gated, and their corresponding sequence selectors SS_1 , SS_3 , etc., have therefore been omitted from Fig. 1). All the keyers are coupled in parallel to a common keying relay K_R , which closes its contacts whenever any keyer passes a pulse to the relay winding.

Each keyer determines whether or not the pulse produced by its corresponding generator shall pass to the output keying relay to produce a mark or shall be blocked to form a space. As indicated above, all pulses in odd-numbered intervals after initiation of the character are marks, so that the odd-numbered keyers need not be controlled, but are permanently conditioned to pass the pulses on to the keying relay. The even-numbered keyers are normally blocked, and would therefore form spaces in the transmitted code character.

To form a dash, an even-numbered keyer is conditioned or gated to pass its pulse, whereby three successive generator pulses are permitted to pass to the relay K_R , forming a dash. The even-numbered keyers K_2 , K_4 , etc. are controlled by respective sequence selectors SS_2 , SS_4 , etc., to determine whether they shall pass or block their pulses. The depressed key of the keyboard KB determines appropriately which of the sequence selectors is to be triggered, to gate on the corresponding keyers, so as to form dashes in the proper relative positions in the code character. The phantom-switch network PS provides the proper connections between the keyboard KB and both the sequence selectors SS and the unit interval generators UIG to carry out these functions.

In addition to these sections of the system, several special purpose sections are included. The eraser circuit E provides for reconditioning the sequence selectors after each character, to make them properly receptive to the depressing of a key for the next character. The monitor circuit M permits the operator to listen to his own transmission, either as a check on his sending or to assist in learning code. The speed control SC adjusts the duration of all the unit interval pulses simultaneously, thereby adjusting the time duration of each character and permitting adjustment of the speed of transmission between wide limits, such as 5 to 125 words per minute.

The specific functioning of each of the above-mentioned portions of the present system will become more clearly apparent from the following detailed description thereof.

The unit interval generator chain

The specific circuit details of the unit interval generator chain will be seen in Figure 3, which shows a circuit diagram of the portion of the system of Figure 1, including the unit interval generators UIG_1 and UIG_{19} , the keyers K_1 and K_{19} , the sequence selectors SS_1 , the eraser circuit E , the monitor circuit S and the speed control SC .

All the unit interval generators UIG_1 to 19 have exactly the same circuit, which is exempli-

fied by the circuit of generator 18 shown in Fig. 3. The generator is formed by a pair of tube sections 21 and 22 which are preferably the two sections of a dual tube, although separate tubes may be used where desired. These tube sections 21 and 22 are illustrated as being triodes, such as of the $6J6$ type, which have been found to be highly satisfactory, although multigrid tubes may be utilized where desired. The anode of the first tube section 21 is coupled to a source of positive potential 23 serving as a common plate supply for all generators, by way of a load resistor R_{202} . Similarly, the anode of the second tube section 22 is coupled to the source 23 through its load resistor R_{203} . The cathodes of both tube sections are connected together and through a common cathode resistor R_{204} to the common negative terminal 24 of the positive potential source 23 ; this terminal 24 may be at ground or chassis potential. The first section grid is connected to the negative terminal 14 through a grid leak resistor R_{201} . The second section grid is connected through a grid leak resistor R_{205} to a reference voltage lead 26 common to all generators connected to the variable tap 27 of the speed control potentiometer SC which has one end connected to the negative terminal 24 and the other end connected to the positive potential source 23 , whereby the potential of lead may be adjustably set to a positive value less than that of the plate voltage source 23 . The first section anode is coupled by a condenser C_{202} to the second section grid. The interconnected cathodes of the two tube sections are coupled through a condenser C_{201} to the first section grid of the following generator in the chain.

The generator has an input lead 28 supplied from the trigger pulse output from the preceding generator, and which triggers the generator at the end of the unit interval pulse of the preceding generator. Also, as indicated above, it is desired to initiate operation of the generator chain at various points to produce unit interval pulse sequences of different lengths corresponding to the lengths of the various characters. The first generator UIG_1 is triggered off by supplying a suitable trigger pulse to its lead 28 from the keyboard and phantom-switch network as described below. Intermediate generators could be triggered similarly by such trigger pulses applied to their leads 28 . However, it is desirable to have a low impedance input coupling for such trigger pulses, and hence such pulses are applied in the present circuit to lead 29 , which is converted to the cathodes of the generator before the one to be triggered, and is then transferred through coupling C_{201} , R_{201} to the grid of the generator to be triggered. For Morse code, only the odd-numbered generators need be triggered, and hence leads 29 are used only with the preceding even-numbered generators and are omitted from the rest.

The generator also has two outputs, namely, lead 31 going to the first section grid of the following generator, and lead 32 coupled to the right section anode, and going through an isolating and grid-current-limiting resistors R_{306} to the keyer K_{18} corresponding to generator 18 , the keyer circuit being described below.

The operation of the unit interval generator chain is as follows:

In the quiescent condition, all the first tube sections are biased beyond cut-off by the voltage drops in the cathode resistors R_{204} . If a positive pulse is applied even momentarily to the left

section grid of generator 1, it serves to render the left section conductive, and current flows through its load resistor R202, which depresses the potential of the left section anode. This change in potential is transferred through condenser C202 to the right section grid, driving the right section to the plate current cut-off, raising the potential of the right section anode. The length of time that the right section will remain cut off is dependent upon the time of constant of the condenser C202 and resistor R205 and upon the reference voltage appearing on lead 26. After this time interval, the right section begins to conduct, which increases the cathode potential and cuts off the left section, which action cumulatively unblocks the right section, causing an abrupt decrease in the anode potential of the right section, terminating the generation of a single positive rectangular pulse at the right anode, which pulse is a unit interval pulse and is supplied to the corresponding keyer input by lead 32.

Coincident with the termination (trailing edge) of this pulse, the voltage across cathode resistor R204 rises and a positive pulse is supplied through condenser C201 and resistor R201 to the left section grid of the following generator. This positive pulse serves to initiate the same cycle of operations in generator 2, which accordingly produces two similar output pulses, namely, a unit interval pulse fed by lead 32 to the corresponding keyer, and a short-duration pulse coincident with the termination of the unit interval pulse which is supplied to the input of the following generator to repeat the same cycle which is repeated in turn by each generator in the chain.

In this way, if the initiating pulse is supplied to the input of generator 1, the unit interval generator chain automatically generates 19 successive unit interval pulses, each supplied to a respective keyer. Where less than 19 pulses are required (for characters having fewer than 19 unit intervals) the initiating pulse is supplied to the lead 29 of the appropriate generator. The initiating pulse is thereby fed by condenser C201 to the input of the succeeding generator to commence the sequence of unit interval pulses at that point. For example, if but one unit interval pulse is desired (as for letter E), the initiating pulse is supplied to lead 29 of generator 13, so that only generator 19 is triggered. If the initiating pulse is supplied to an intermediate generator, such as, for example, to the cathodes of generator No. 10, then only generators 11 to 19, inclusive, produce the sequence of unit interval pulses, now 9 in number, suitable for a code character having a duration of 9 unit intervals.

The speed control

The control of the duration of the rectangular pulse produced by each generator and supplied to the keyer, that duration being the unit interval, is dependent upon the reference voltage on lead 26, which in turn is regulated by the speed control potentiometer SC. Since this potentiometer SC adjusts the reference voltage for all of the right section grids of all of the generators simultaneously, it will be seen that it simultaneously varies the unit interval for all 19 intervals, and thereby varies the duration of all of the code characters in equal ratio. This is, accordingly, a simple and convenient speed control which can determine how many characters or words per minute can be transmitted by the apparatus without overlap of output code signals.

8 The keyer section

The keyer section of the present system is comprised of 19 keyer circuits K1 to K19. In the present instance, these are illustrated as triode tube sections 30 and again may be sections of a dual tube or independent tubes. Types 6J6 tubes have been found satisfactory. Alternatively, multigrid tubes may be used where desired.

Each of the keyer tubes 30 has its input grid 10 coupled to the unit interval pulse output of a corresponding unit interval generator, through a respective isolating and grid-current-limiting resistor R306. The cathodes of all the keyer tubes 30 are directly connected together and to one 15 terminal of the winding of the keying relay KR. The other terminal of this relay winding is connected to a source of low positive potential which may be obtained for example, by means of a voltage divider formed by resistors R723 and R724 connected between a source of high positive voltage 33 and the common negative terminal 20 24. This low positive potential thus derived is chosen to have a value which, in the absence of signal input to the keyer grid, maintains all the 25 keyer plate currents cut off, so that no current flows through the keying relay KR. However, when a positive unit interval pulse is derived from any one of the unit interval generators and is applied to the corresponding keyer input grid 30 (and provided that the anode of the keyer 30 in question is coupled to the positive potential source 33 as described below) the keyer tube 30 will conduct during the application of the unit interval pulse thereto, which will cause current to 35 flow for that interval in the winding of keying relay KR, which will close its contacts for that interval to produce a corresponding output pulse.

To control which of the keyers will pass its input pulses and which will remain blocked, so as 40 to form the desired code characters, the anode voltages of the keyers are gated by the sequence selectors, as described hereinbelow. However, as mentioned above, there is no need to control the odd-numbered keyers, since all the odd-numbered intervals beginning with the first odd interval utilized, are mark intervals. Therefore, each of the odd-numbered keyers has its anode connected directly to the positive potential source 33, as is 45 illustrated with respect to keyer K19 in Figure 3. However, depending upon the particular code character being transmitted, certain of the even-numbered keyers are required to remain blocked to prohibit passage of a unit interval pulse therethrough, to form a spacing interval, while others 50 may be required to be unblocked to cause an even marking interval which cooperates with the adjoining odd marking intervals to form a dash. The even keyers must therefore be gated in a manner corresponding to which code character 55 is being transmitted. This gating is performed by the respective sequence selectors, of which only the even-numbered ones are required in the case of International Morse code. It will be understood that, in the case of other codes, some or all of the odd-numbered sequence selectors may be necessary.

The sequence selector section

Figure 3 also illustrates the circuit diagram of 70 one sequence selector S518, the circuit diagram for the others being identical thereto. The sequence selector is formed by a grid-controlled gas discharge tube 34, such as a 2D21 thyratron. The anode of selector tube 34 is coupled through a load resistor R411 to a lead 21 and thence

through the normally closed contacts 38 of the eraser relay ER to be described, to the source 33 of high positive potential. The screen grid of tube 34 is connected to the source 33 through resistor R413 and is also connected to the cathode, which in turn is connected to the negative terminal 24 through a resistor R412. The input grid is connected through a grid leak resistor R408 to negative terminal 24, and has an input lead 36. The cathode of tube 34 is also connected to the anode of the corresponding keyer tube 30 by a lead 35.

It will thus be seen that, so long as tube 34 remains non-conductive, the potential of the anode of the keyer tube 30 is determined by the voltage divider formed by resistors R413 and R412. These resistors are so chosen that the keyer tube has insufficient anode voltage to conduct and remains blocked despite application of a positive potential to its grid. However, when sequence selector tube 34 becomes conductive, it draws current from the source 33 through contacts 22, lead 21 and resistor R411, which current also flows through cathode resistor R412 and raises the voltage thereacross, whereby the anode potential of the keyer tube 30 is raised to a value sufficient to gate on the keyer tube 30, and condition it to become conductive upon application of a unit interval pulse to its input grid.

Control of the conduction of the sequence selector tubes is derived from the keyboard KB through the phantom-switch network PS, whereby, upon actuation of any key of the positive potentials are applied to the proper sequence selector keyboard KB corresponding to a code character, leads 36 to gate on the appropriate keyers to form the corresponding code character.

The eraser circuit

In the operation of the system described above, it will be apparent that upon actuation of a key of the keyboard corresponding to a code character requiring gating on one or more keyer stages, the corresponding sequence selector or selectors become conductive. Because of the normal operating characteristics of gas discharge tubes this conductive condition persists even after termination of the transmission of the code characters involved. If this condition were permitted to continue, it will be apparent that the following code character might not be accurately transmitted, since the wrong sequence selectors might be then conductive.

In order to prevent this condition from arising, the eraser circuit E is utilized. This comprises a tube 37, also of the gas discharge type, and which may be similar to the sequence selector tubes. The cathode of the eraser tube 37 is connected to the negative terminal 24 by means of a cathode resistor R516. The anode of the eraser tube 37 is connected through the winding of the eraser relay ER and resistor R719 to the lead 21, and thence through the eraser relay contacts 38 to the high positive potential source 33. The input grid of the eraser tube 37 is coupled to the cathodes of unit interval generator UIG19 by means of a coupling condenser C503 and input resistor R514.

At the completion of the sequence of unit interval pulses, a positive pulse is produced at the cathodes of UIG19 which is transmitted to the eraser tube 37 and triggers the tube 37 to render it conductive. This draws current through the winding of the eraser relay ER and opens its contacts 38 to remove anode potential from lead

21. Thereby anode potential is removed from all of the sequence selector tubes 34, which are then restored to their original non-conductive condition, and remain non-conductive until application of subsequent control impulses upon their input leads 36. The eraser tube 37 also automatically restores itself to the proper condition for performing the next erasing function at the end of the following coding character, since by opening contacts 38 of the eraser relay ER it removes its own plate supply and restores tube 37 to its non-conductive condition.

The phantom switch network and keyboard sections

The keyboard KB represents the portion of the apparatus which is manipulated by the operator, and is preferably arranged in a form similar to the standard typewriter keyboard with the added provision of the special Morse code characters AR, SK, AS, and BT. In addition, an error or "clear" key CL is provided, whose purpose and operation is described below. Each of the keys of the keyboard operates a switch means which, by virtue of the phantom-switch network PS, properly operates the unit interval generator chain and the sequence selector section of the apparatus.

As indicated above, the keyboard and phantom-switch network must function to assure two conditions upon depressing any key:

- 30 (1) The unit interval generator chain must be started at the proper generator to produce unit interval pulses equal in number to the length (measured in unit intervals) of the code character represented by the depressed key; and
- 35 (2) The appropriate sequence selectors must be triggered on to provide the correct number of dashes in the correct positions in the character.

For these purposes, a maximum of 6 separate triggering or initiating pulses is required for each character. One triggering pulse is necessary to initiate the sequence of unit interval 45 pulses. As indicated above this sequence may require any odd number of unit interval pulses up to 19, depending upon the character being sent, and accordingly it is necessary for the keyboard and phantom-switch network to be able 50 to apply this initiating pulse to any one of ten points in the unit generator chain, namely, the nine leads 29 (Fig. 3) and the input to UIG1.

Figure 2 illustrates for each code character the particular generator to which the triggering 55 pulse must be applied. In each case, this is the generator having the same number as the interval preceding the first mark in the character. For example, for A, UIG14 must be triggered; for B, UIG10; for C, UIG8, etc. For zero and 60 comma, UIG1 must be triggered. This is also set out in the generator and sequence selector triggering table, set out below.

In addition to the single generator triggering pulse, up to 5 further pulses are necessary for 65 triggering appropriate sequence selectors.

As indicated above, all odd-numbered unit interval pulses are directly passed by the corresponding odd-numbered keyers to produce dot marks in the output. Wherever a dash mark is desired, according to the present invention, the even-numbered keyer at the center interval of the three unit intervals which form the dash mark is gated on, so that the even-numbered keyer passes a unit interval pulse also. Under 70 these circumstances three successively numbered 75

11

keyers pass unit interval pulses. The combination of these three unit interval pulses forms the dash mark.

As will be seen from Figure 2, dashes occur in various positions among the 19 intervals but gating only of even-numbered keyers is required by virtue of the special convention by which the Morse code was set up, using single-unit dots and spaces and triple-unit dashes. The required gating of each of the even-numbered keyers is under the control of the corresponding even-numbered sequence selector. Examination of the code chart of Figure 2 will reveal that certain characters have no dashes whatever and hence require no gating. Other characters have from 1 to 5 dashes, requiring up to five keyers to be gated and correspondingly requiring up to 5 sequence selectors to be triggered. The particular requirements for the complete Morse code are shown in the following generator and sequence selector triggering table, listing opposite each code character the numbers of the sequence selectors to be triggered and the number of the

Code Character	Sequence Selectors To Be Triggered	UIG to be Triggered
A	18	14
B	12	10
C	10 16	8
D	14	12
E		18
F	16	10
G	12 16	10
H		12
I		16
J	10 14 18	6
K	12 18	10
L	14	10
M	14 18	12
N	16	14
O	10 14 18	8
P	12 16	8
Q	8 12 18	6
R	16	12
S		14
T	18	16
U	18	12

SK	12 18	4
AS	12	8
BT	8 18	6
Period	6 12 18	2
Question Mark	10 14	4
Comma	2 6 14 18	0

From this table it will be seen that each character has a specific combination of sequence selectors which must be triggered. Thus, for A, sequence selector 18 must be triggered; for B, selector 12; for Y, selectors 8, 14 and 18; for zero, selectors 2, 6, 10, 14 and 18. To be triggered, each of these sequence selectors must have a positive voltage pulse applied to its input lead 36, from the keyboard KB and phantom-switch network PS.

One manner in which this requirement can be met is by the use of six-pole single throw switches individually actuated by respective buttons of the keyboard. One set of contacts of such six-pole switches is assigned to trigger the proper unit interval generator. For this purpose, one contact of each pair is connected to a positive potential source, and the other contact

12

for a particular character is connected to the proper one of the ten leads leading to the ten unit interval generators to be triggered, according to the above Triggering Table. For example, this contact for character A would be connected to the lead going to generator 14; for character B, to the lead going to the generator 10; etc. Where desired, proper voltage dropping or isolated resistors may be connected individually to such contacts.

Similarly, the remaining 5 contact sets for each character switch may be connected to the proper ones of the 9 sequence selector inputs, as indicated by the above triggering chart. However, when this is done a number of problems arise, among which the most important is the fact that the resulting network provides a number of shunt paths which either supply triggering potential to undesired sequence selectors or so reduce the resistance of its input circuit as to prevent triggering of the desired sequence selector. Furthermore, considerable mechanical difficulty and complexity is experienced in mounting some 44 six-pole switches in as compact a space as is taken by a conventional typewriter keyboard.

These disadvantages are overcome by the present invention, which further provides a greatly improved type of network suitable for the requirements of this system, in which each character key of the keyboard need actuate but a single-pole single-throw momentary contact switch, which is easily mechanically realizable in the confined space available. At the same time the problems incident to back coupling or shunt paths are eliminated. In effect, the phantom-switch network PS permits a single-pole switch to serve the function of a multipole switch in turning on several circuits.

The phantom-switch network PS of the present invention will be more readily understandable by reference to Figure 4, illustrating the manner in which this phantom-switch network PS is built up. For clarity, this figure shows only three representative character keys I, C and Z on the keyboard, but it will be understood that the remaining 41 keys are connected in accordance with the principles to be described.

Each key of the keyboard is directly connected mechanically to a single-pole switch. The switch corresponding to the character I is indicated schematically by the reference numeral 101; the switch corresponding to the letter Z by 102; and the switch corresponding to the letter C by 103. Each of these switches has one terminal connected directly to a suitable source of positive potential 104, which may be the same as source 23 or 33 of Figure 3. The other terminal of switch 101 is connected through an isolating resistor 114 also serving as a voltage dropping resistor to the appropriate unit interval generator. From the triggering table above, it will be seen that for the digit 1 the unit interval generator 2 must be fed the triggering pulse and accordingly resistor 114 is connected to the cathodes of unit interval generator 2. Similarly Z-switch 102 is connected through a similar resistor 112 to its appropriate unit generator which is here No. 3. C-switch 103 is connected through a similar resistor 113 to its unit interval generator which will be seen to be also No. 3. The parallel connection of C-switch 103 and Z-switch 102 to the same unit interval generator has no effect on the system, since only one of these switches is closed at any time and by the means herein-

below described, no paths to ground or to the negative potential terminal from the other switches which are open are present. It will be understood that each of the remaining 41 character switches is connected through its individual isolating and voltage dropping resistor to its proper unit interval generator illustrated in the table above.

Reference to Figure 2 will show that the code symbol for digit 1 is formed by one dot and four dashes. This immediately indicates that four sequence selectors must be triggered to gate on four appropriate keyers. Figure 2 shows that the center intervals of these four dashes are numbered 6, 10, 14 and 18. Accordingly, sequence 10 15 selectors numbered 6, 10, 14 and 18 must be triggered, as is indicated on the triggering table hereinabove. For this purpose the terminal of switch 10 20 **f01** is connected through respective isolating elements **114**, **115**, **116** and **117** to respective voltage dropping resistors **118**, **119**, **120** and **121** and then to the respective input circuits sequence 25 selectors **6**, **10**, **14**, and **18**. The manner in which such connection is made is illustrated in the case of sequence selector **10**, showing its input resistor **R408** and its cathode resistor **R412**.

The isolating elements **114** may be unidirectionally conductive elements such as crystal rectifiers or germanium diodes, or may be neon or like gas-filled bulbs. A suitable and preferred element has been found to be a neon bulb of the **NE21** type. The voltage of source **104** is chosen to have a sufficient value and magnitude so as to cause conduction of the neon bulbs **114** to **117**. The isolating resistors **118** to **121** in association 30 with sequence selector input resistors **R408** provide voltage dividers which apply appropriate triggering potentials to the sequence selectors **6**, **10**, **14** and **18**, as desired.

Reference to Figure 2 and the above triggering table shows that the character **Z** is formed by two dashes and two dots, requiring gating on of the keyers **10** and **14** and consequent triggering of selectors **10** and **14**. Accordingly, the terminal of the **Z**-switch **102** is connected through isolating element **122** and resistor **123** to the input of sequence selector **10**, and through isolating element **124** and resistor **125** to the input of sequence selector **14**, and operates similarly to gate on the proper sequence selectors for this character. Similarly, the code character **C** is formed by two dashes and two dots, requiring gating on keyers **10** and **16**, which is done by the connection of the terminal of **C**-switch **103** to sequence selector **10** by way of isolating element **126**, resistor **127** and to sequence selector **16** by isolating element **128** and resistor **129**.

The remaining characters of the keyboard are connected to their respective sequence selectors indicated on the triggering table above in the same manner, with individual isolating elements and connecting voltage dropping resistors.

It will be apparent that stray shunt paths and back voltages are prevented by this system. For example, referring to Figure 4, three separate connections are shown to the input of sequence selector **10**. If, for example, the key **Z** is depressed, the appropriate triggering potential is applied to sequence selector **10**. Through element **122** and resistor **123** this triggering potential is also necessarily applied to the series circuit of resistor **119**, element **115**, element **116** and resistor **120** to the input to sequence selector **14**. However, by the voltage divider **123**, **R408**, this potential is made too low to trigger 70 75

both neon bulbs **115** and **116**, which remain open-circuited and hence isolate the undesired sequence selector **14** from the system. Similarly, other sequence selectors are isolated and only the desired selector can be triggered. In this way, the effects of the remaining connections not directly utilized or desired are eliminated and only the desired sequence selectors are actuated.

Monitor circuit

In many applications of the present system, it is desirable to be able to listen to the code transmission being produced. This is not only useful for monitoring purposes, and to assure that the speed control is set sufficiently high to avoid overlap of characters at the normal "typing" speed, but is also extremely useful in assisting in instruction of Morse code. By a monitor circuit such as the one now to be described, it is possible for an operator to produce Morse code without any knowledge whatever of what the code may be; merely by pressing a particular letter or digit of the keyboard, the Morse code character is automatically produced and heard. This provides a simple and ready means to learn Morse code by actual aural practice.

For this purpose, a monitor circuit **M** is provided, which, as shown in Figure 3, essentially consists of a phase shift oscillator formed by a triode or other type of tube **41** having its anode coupled to its input grid by a phase shift network **51**.

The anode is also coupled to a high positive potential source, which may be source **33**, in series with a jack **J**. The cathode is coupled to a low positive potential source such as **23**, or to negative terminal **14**, through a cathode biasing resistor **R632** which normally maintains the tube **41** cut off. The circuit thus provides a tone oscillator of a frequency of approximately 1,000 cycles or other desired value.

The grid of monitor tube **41** is coupled to the cathodes of the keyer tubes **K1** to **K19**. In this way the normally blocked monitor oscillator **M** is unblocked by the pulses forming the code character as supplied to the keying relay **KR**, and a suitable reproducer coupled to the jack **J** permits listening to the code transmission produced.

The present invention also includes means for 50 checking operation of the circuit at any time. On the keyboard there is provided a "clear" or **CL** key, which operates to trigger the first unit interval generator, without operating any of the sequence selectors. If all unit generators are operating satisfactorily, a sequence of ten dots will be produced, which can be heard by means of the monitor circuit. Any trouble will be detected by the non-appearance of one or more of these dots, the position of the "missing" dot being indicative of the defective generator stage.

While the present invention has been described as applied to the International Morse code, it will be understood that it may be used with any type of code, either with code characters of equal length or of unequal length. In any code, the code characters may be broken down into unit intervals. In general, the number of unit interval generators is equal to **N**, the number of intervals in the longest character. In the most general case, each generator may initiate the pulse sequence, and is provided with a control lead such as **29** in Fig. 3. As many keyers are used as there are generators. As many sequence selectors are used as necessary to obtain all code

characters; in the most general case, there will also be N.

Where all code characters are of equal length, all leads 29 are omitted, and the full pulse sequence is generated for each character. In particular, for the teletype code, using five unit intervals, any one of which may be either a space or a mark, five unit interval generators, five keyers and five sequence selectors are used. Once the code is set forth in the manner of Figure 2, the sequence selector triggering chart is easily read off, and leads directly to the connections between the keyboard switches and the selectors, following the principles already given.

It will be understood that the present invention is not limited to the specific circuits shown. Many types of single-pulse or univibrator circuit are known, and any circuit capable of producing the unit interval pulse sequence of selective total length may be employed. Similarly, the keyer circuits shown are one form of the general type of circuit known as gating circuits, and many equivalent gating circuits capable of performing the same functions may be substituted. Also, the specific sequence selector circuits described represent but one out of many types of circuit suitable for properly controlling the keyers, and others may be used in the present system.

Accordingly, the present invention is not to be deemed limited by the above description, which is solely illustrative, since many other types of circuit may be used in place of those described herein, and the invention is defined only by the claims granted to me.

What is claimed is:

1. A keyboard-operated code producer for International Morse code, comprising a keyboard having a plurality of keys each corresponding to one character of said code, a like plurality of normally open single pole momentary contact switches mechanically coupled respectively to said keys to be actuated thereby, each of said switches having first and second terminals, a source of direct potential coupled to all said first terminals, a 19-stage uni-pulse generator chain having nineteen cascaded generators, each of said generators being adapted in response to receipt of a trigger pulse to produce a single output rectangular pulse and to supply a trigger pulse to the next generator of said chain coincidentally with the termination of its own rectangular pulse to thereby trigger said next generator in similar manner to produce a further output pulse and a further trigger pulse for the following generator, all said output pulses having uniform duration, whereby application of a trigger pulse to any generator of said chain produces a sequence of output uniform-duration rectangular pulses equal in number to the number of generators from the generator first triggered to the end of said chain, the second terminal of each key switch being coupled to the input of that one of said generators from which to the end of said chain there are as many generators as there are unit intervals in the character corresponding to said key, whereby upon depressing said key to close its respective switch, a trigger pulse is applied to the appropriate point of said generator chain to initiate a sequence of output pulses equal in number to the interval length of the respective character, nineteen keyer circuits, each of said generators having its output coupled to the input of a respective keyer circuit to supply its respective output rectangu-

lar pulse thereto, a keying relay having a pair of output contacts and a winding, the outputs of all said keyer circuits being connected in parallel to said keying relay winding whereby said contacts are operated in correspondence with pulses passing individually through said keyer circuits, nine sequence selector circuits coupled to the nine even-numbered keyer circuits, each being adapted upon excitation by a contact pulse to gate-on its respective keyer circuit, and means coupling the second terminal of each of said keyer circuits to those of said sequence selector circuits corresponding to keyers whose input pulses from said generator chain have interval positions corresponding to the positions of the center intervals of the dash marks of the character corresponding to said each key, whereby upon actuation of any key of said keyboard, said generator produces a sequence of pulses of number equal to the interval length of the code character corresponding to said actuated key, and said keyers pass to said keying relay only those pulses corresponding to dots and dashes of said code character.

2. A keyboard-operated code producer for a telegraphic code of the mark and space type whose code characters are of different numbers of unit intervals in length, comprising a keyboard having a plurality of keys each corresponding to one character of said code, a like plurality of normally open single pole momentary contact switches mechanically coupled respectively to said keys to be actuated thereby, each of said switches having first and second terminals, a source of direct potential coupled to all said first terminals, a plural-stage uni-pulse generator chain having a number of cascaded generators equal to the number of unit intervals in the longest character of said code, each of said generators being adapted in response to receipt of a trigger pulse to produce a single output rectangular pulse and to supply a trigger pulse to the next generator of said chain coincidentally with the termination of its own rectangular pulse, to thereby trigger said next generator in similar manner to produce a further output pulse and a further trigger pulse for the following generator, all said output pulses having uniform duration, whereby application of a trigger pulse to any generator of said chain produces a sequence of output uniform-duration rectangular pulses equal in number to the number of generators from the generator first triggered to the end of said chain, the second terminal of each key switch being coupled to the input of that one of said generators from which to the end of said chain there are as many generators as there are unit intervals in the character corresponding to said key, whereby upon depressing said key to close its respective switch, a trigger pulse is applied to the appropriate point of said generator chain to initiate a sequence of output pulses equal in number to the interval length of the respective character, a plurality of keyer circuits equal in number to the number of said generators, each of said generators having its output coupled to the input of a respective keyer circuit to supply its respective output rectangular pulse thereto, a keying relay having a pair of output contacts and a winding, the outputs of all said keyer circuits being connected in parallel to said keying relay winding whereby said contacts are operated in correspondence with pulses passing individually through said keyer circuits, a plurality of sequence selector circuits

17

coupled to respective ones of said keyer circuits, each being adapted upon excitation by a contact pulse to gate-on its respective keyer circuit, and means coupling the second terminal of each of said key switches to appropriate ones of said sequence selector circuits to apply control pulses from said source thereto upon actuating any one of said keys to cause said keyer circuits to pass only those of said sequence pulses required to form the code character corresponding to said actuated key, whereby said keying relay winding is energized by a sequence of pulses having duration and spacing corresponding to said code character.

NATHANIEL G. A. DORFMAN.
